SILVERWARE DISPLAY PANEL FOR A PACKAGE OR SIMILAR ARTICLE

Samuel Braun, Rye, N.Y., assignor to Metal Design Products, Inc., Taunton, Mass., a corporation of Massachusetts

Filed Feb. 15, 1968, Ser. No. 10,585

Term of patent 14 years

U.S. Cl. D9—253
Int. Cl. D9—99

FIG. 1

FIG. 2

FIG. 3

FIG. 4

FIG. 1 is a front elevational view of a silverware display panel for a package or similar article showing my new design;

FIG. 2 is a side elevational view thereof;

FIG. 3 is an end elevational view thereof taken from the lower end of FIG. 1; and

FIG. 4 is an end elevational view thereof taken from the upper end of FIG. 1.

The dominant portions of my new design are those shown in solid lines.

I claim:

The ornamental design for a silverware display panel for a package or similar article, as shown and described.
